Inventor:

Wallace A. Bartlett

UNITED STATES PATENT OFFICE.

WALLACE A. BARTLETT, OF WASHINGTON, DISTRICT OF COLUMBIA.

PROJECTILE.

SPECIFICATION forming part of Letters Patent No. 308,944, dated December 9, 1884.

Application filed October 3, 1884. (No model.)

To all whom it may concern:

Be it known that I, WALLACE A. BARTLETT, residing at Washington, in the District of Columbia, have invented certain new and useful 5 Improvements in Projectiles, of which the following is a specification, reference being had therein to the accompanying drawings.

This invention relates to projectiles of frangible material, intended to be used principally to contain chemicals for use in extinguishing fires.

The invention consists in the construction of such projectiles, as hereinafter pointed out and claimed.

15 Glass-bottles containing a chemical mixture, known as "hand-grenades," are largely in use for extinguishing fires, the grenade being used by throwing it violently into the fire, thus rupturing the bottle and releasing the 20 contents. I propose to make such bottles in form of a projectile to be thrown from an air, spring, or other gun to points not readily accessible for hand-grenades.

The projectile may contain a coiled line, instead of chemicals, for use as a fire-escape or 25 life-line.

In the drawings, Figure 1 is an elevation of 30 a flexible sleeve or stocking which forms the guiding-feather of the projectile. Fig. 2 is a longitudinal section of a projectile with the sleeve or stocking applied. Fig. 3 is a similar view of a projectile with stocking turned up, as for shipment. Fig. 4 is a longitudinal section of a projectile having flexible stocking divided into separate feathers. Fig. 5 is a similar view of another form of projectile. Fig. 6 is a similar view of a projectile with life-line. Fig. 7 is a plan of one form of feather, detached.

40 A represents the body of the projectile, which is preferably of glass or earthenware; but thin metal may be employed under some circumstances. The body has a groove, B, near the base, in which a stocking or sleeve, C, may be secured either by glue or cement or by sewing or tying. The stocking C is preferably of textile material or felt, though other materials having same general characteristics may be used. I have found canton-flannel to 45 answer a good purpose. The stocking may be made tubular, as in Fig. 1, or disk form,

as in Fig. 7, and in the latter case is preferably split, as at c c c c and c' c', and the corners of the sections may be rounded, as at c² c². The stocking is preferably turned up over the 55 outside of the projectile, as in Fig. 3, for packing and transportation, and the projectile may be put in the gun with the stocking in that position. As the projectile leaves the gun the stocking will turn back and form a 60 projecting feather to guide the projectile in its flight. The front of the projectile may be protected against accidents in transportation by a ring, D, of twine, paper, or fabric, and this ring D, as well as the stocking C, will act 65 as a gas check in the gun and also protect the gun-barrel. The ring D may be in a groove or against a shoulder in the projectile. The stopper E may be either in front or rear of the projectile, and may be applied in any well-known way for stopping bottles. As shown in Fig. 5, the stopper projects and will be driven in when the projectile strikes, and release the contents, whether the bottle breaks or not.

75 The modification, Fig. 6, for throwing lines, does not require a guiding-feather. The line will be coiled in the projectile, and as it reels out will itself serve as a feather. The conical point of the projectile may be made heavy, to 80 keep it "point on."

The form of the body of the projectile is preferably cylindrical, but is subject to variation within reasonable limits. I have thrown ordinary vials, with a fabric "stocking," from 85 a pneumatic gun with good range and accuracy.

I am aware that cartridge-cases, to contain powder, of paper and of fabric have been secured to bullets by a thread pressing the front 90 of the cartridge-bag into a cannelure of the bullet. In such case, however, the powder-bag does not and cannot serve as a guiding-feather to the projectile, as it is torn off by the explosion of the powder or by the rifling in 95 the gun.

I am also aware that a bomb-lance has been described having an elastic guiding-feather of thin metal.

I claim—

1. As a new article of manufacture, a hollow projectile of frangible material filled with

a fire-extinguishing compound and provided with a guiding-feather of flexible material, substantially as described.

2. A hollow projectile of frangible material, having a non-metallic guiding-feather of flexible material permanently attached near the base thereof, substantially as described.

3. The combination, with the body of a projectile of frangible material, of a stocking of flexible material secured near the base, so as to extend beyond the base when turned back, and a ring of similar material surrounding the body near the front.

4. The body of a projectile having a stocking of the character described secured at the base, and having a projecting stopper which will be driven in when the point of the projectile strikes, substantially as described.

In testimony whereof I affix my signature in presence of two witnesses.

WALLACE A. BARTLETT.
